UNITED STATES PATENT OFFICE.

CASSIUS M. THOMPSON, OF MANCHESTER, NEW HAMPSHIRE, ASSIGNOR TO W. H. McELWAIN COMPANY, OF BOSTON, MASSACHUSETTS, A CORPORATION OF MASSACHUSETTS.

REINFORCED INNERSOLE.

1,175,200.

Specification of Letters Patent.

Patented Mar. 14, 1916.

Application filed January 12, 1914. Serial No. 811,514.

To all whom it may concern:

Be it known that I, CASSIUS M. THOMPSON, a citizen of the United States, and resident of Manchester, in the county of Hillsboro 5 and State of New Hampshire, have invented certain new and useful Improvements in Reinforced Innersoles, of which the following is a specification.

The present invention relates to inner soles for boots and shoes, such inner soles being of the type having an upstanding rib to receive the stitches by which the upper and welt are united to the inner sole.

The primary object of the invention is to enable inner soles of this character to be made from thinner and less expensive stock than has heretofore been required, while at the same time enabling a rib which in part is an integral portion of the surface of the 20 inner sole to be produced thereon.

My objects above stated are accomplished by reinforcing the inner sole before channelling and then channelling the reinforced inner sole so as to form a lip which may be made into a stitch-receiving rib and consists in part of the reinforcement and in part of the material of the inner sole. The inner sole thus produced may be further substantially reinforced by any of the means 25 or according to any of the principles now known or which may hereafter be adopted.

In the accompanying drawings, Figure 1 is a perspective view of an inner sole reinforced according to my invention prior to 30 channelling. Fig. 2 is a perspective view of the inner sole after the stitch-receiving rib has been formed thereupon and further reinforced. Fig. 3 is a cross section of the inner sole shown in Fig. 2 and taken on line 40 3-3 of Fig. 2.

The same reference characters indicate the same parts in all the figures.

In producing an inner sole according to my present invention I provide a composite 45 sole blank *a* consisting of two layers *b* and *c*, one of which, as *b*, may be considered the body of the inner sole, and the other of which, *c*, may be considered the reinforcing layer. The body layer may be made of 50 leather, leather board, or any other stock which is commonly used for insole stock or which may be used for that purpose. The reinforcing layer is preferably of some sufficiently strong and inexpensive material such 55 as cotton duck or other tough fabric. It is

to be understood that in naming the materials which I prefer to use in producing my invention, I do not thereby intend to limit the invention to these or any other particular materials. I may, within the scope of 60 my invention, use any materials whatever which answer the essential requirements of the invention as hereinafter set forth in this specification and in the appended claims. The reinforcing layer is firmly united to the 65 body layer of the inner sole in any suitable or approved manner, as by a coating of adhesive, or by stitches or other suitable fastenings. If desired the layers may be united together before the sole blank *a* is 70 died out from the sheet of stock, although shaped or died out blanks of body stock and of reinforcing stock may equally well be united together after being cut to shape.

The blank constructed essentially as shown 75 in Fig. 1 is now channeled and the lip formed by cutting the channel is turned up. I do not restrict my invention to any particular mode of cutting the channel and turning up the lip, as these operations may be performed 80 in any manner desired. For my own purposes I prefer to cut the channel so that it extends from a line well within the edges of the inner sole toward such edges, and terminates at a distance from the edges of the 85 inner sole equal to the amount by which such edges are intended to project beyond the stitch-receiving rib. In other words, the channel is so cut that the flap thereof is turned up from within the edges outwardly. 90 The channel cut is sufficiently deep so that it not only slits the reinforcing layer, but it also cuts into the body layer and forms a lip *d* from the stock of said body layer. 95 When the channel flap is turned the lip *d* and the part *e* of the reinforcing layer overlying such lip are turned, making a composite rib formed in part of the lip *d* and in part of the lip *e*.

The inner sole as thus made and without 100 being further reinforced may, if desired, be used in a shoe, but if it is desired to strengthen or stiffen the inner sole and rib further, they may be further reinforced. 105 For instance, an inner sole made as above described may be reinforced in the manner illustrated in the patent to Rollins No. 1,070,069 by laying a strip *f* in the channel and against the inner side of the rib, and by afterward laying a sheet *g* on the surface of 110

the inner sole within the rib, causing the edges g' of such sheet to lie against the inner side of the rib. Or, if desired, whatever further reinforcement is desired may be applied according to other known methods, or otherwise.

The advantages of the inner sole made and having the characteristics as above described are mainly that a rib may be formed in part integrally of the body of the inner sole which is much thinner than has heretofore been required, that the outer reinforcing layer makes such rib sufficiently strong to hold the stitches, and that thereby it is possible to use lighter and less substantial stock than has been required heretofore. A very thin rib d has a sufficiently firm attachment to the body of the inner sole of which it is an integral part to prevent tearing. The outer reinforcing layer e formed as an integral part of the sheet c , strengthens the rib d and provides with the latter a composite rib capable of opposing powerful resistance to the tearing out of stitches. The inner sole formed of these two layers, and the rib made out of them in the manner described, has substantially as great strength as, if not greater than, inner soles made wholly out of the best leather stock, but as such a composite inner sole can be made of less expensive material, its use results in a marked economy in shoemaking. Again, the inner sole has great flexibility, being more flexible than a leather inner sole of the same strength, by reason of the use of a thinner piece of leather than that required for an all leather inner sole to which the requisite strength has been given by the reinforcement of duck or other fabric. Finally an inner sole so made is capable of being reinforced by any of the means and methods which have already been found suitable for all leather or composite inner soles.

What I claim and desire to secure by Letters Patent is:—

1. An inner sole composed of a body layer and a reinforcing layer and having a rib formed by channeling through the reinforcing layer and into the body layer and turning up the parts cut thereby.
2. An inner sole consisting of a body layer and a reinforcing layer united thereto and substantially co-extensive with a surface thereof, said inner sole having a composite lip formed of a flap cut from the body layer and a flap cut from the portion of the reinforcing layer which overlies said body layer.
3. An inner sole consisting of a body having an integral upturned lip, and a reinforcing layer lying against and united to the surface of the body, both inside and outside of said lip; said reinforcing layer itself having an integral lip beside and in contact

with the lip of the body on the outer side only thereof.

4. An inner sole comprising a body layer, 65 a sheet of reinforcing material overlying said body layer, and an upstanding rib formed of a lip integral with the body layer and a lip integral with the reinforcing layer, the inner sole having a channel cut through 70 the reinforcing layer and into the body layer located within said rib.

5. An inner sole comprising a body layer, a sheet of reinforcing material overlying said body layer, and an upstanding rib 75 formed of a lip integral with the body layer and a lip integral with the reinforcing layer, the inner sole having a channel cut through the reinforcing layer and into the body layer located within said rib, and a reinforcing 80 strip occupying said channel and having an upstanding edge lying against the inner face of said rib.

6. An inner sole comprising a body portion having an upturned integral channel flap, and a reinforcing layer overlying the surface of the body from which said flap is turned up, on both the inner and outer sides of the flap, and having an integral cut lip upturned and lying against a side of said flap, said flap and portion together forming 90 a stitch-receiving rib.

7. A composite inner sole comprising a body layer, an overlying reinforcing layer, and a reinforcing strip, said inner sole having a stitch-receiving rib formed in part of a flap integral with the body layer, in part of a flap integral with the reinforcing layer and lying against the outer surface of said first-named flap, and in part by said strip, 100 which lies within the first-named flap.

8. An inner sole consisting of a body having an upturned lip, and a reinforcing layer of the same area and marginal outline as the body overlying the surface of the body both 105 inside and outside of said lip, and having an opening located conformably to the lip, through which the lip projects, and also having an integral upturned flap lying against one side of the lip.

9. An inner sole consisting of a body having an upturned lip, a layer attached to the surface of said body both within and outside of said lip and against the outer side of the lip, there being a channel extending through the reinforcing layer and into the body on the inner side of the lip, and a reinforcing strip occupying said channel.

In testimony whereof I have affixed my signature in presence of two witnesses.

CASSIUS M. THOMPSON.
